US00D652041S

(12) **United States Design Patent**
Andre et al.

(10) **Patent No.:** US D652,041 S
(45) **Date of Patent:** ** Jan. 10, 2012

(54) **ELECTRONIC DEVICE**

(75) Inventors: **Bartley K. Andre**, Menlo Park, CA (US); **John M. Brock**, San Francisco, CA (US); **Matthew Phillip Casebolt**, Fremont, CA (US); **Brett William Degner**, Menlo Park, CA (US); **Ron Alan Hopkinson**, Campbell, CA (US); **Eugene Kim**, San Francisco, CA (US); **Chris Ligtenberg**, San Carlos, CA (US); **John Raff**, Menlo Park, CA (US); **David Yeh**, Redwood City, CA (US)

(73) Assignee: **Apple Inc.**, Cupertino, CA (US)

(**) Term: **14 Years**

(21) Appl. No.: **29/388,769**

(22) Filed: **Apr. 1, 2011**

Related U.S. Application Data

(62) Division of application No. 29/379,432, filed on Nov. 19, 2010, now Pat. No. Des. 637,193.

CLAIM

The ornamental design for an electronic device, as shown and described.

DESCRIPTION

FIG. 1 is a top, front, left perspective view of an electronic device showing our new design;
FIG. 2 is a top view thereof;
FIG. 3 is a bottom view thereof;
FIG. 4 is right side view thereof;
FIG. 5 is a left side view thereof;
FIG. 6 is a rear view thereof; and,
FIG. 7 is a front view thereof.

1 Claim, 5 Drawing Sheets
